UNITED STATES PATENT OFFICE

167,936

CUP

Donald E. Folley, Fayetteville, N. Y., assignor to
Onondaga Pottery Company, Syracuse, N. Y., a
corporation of New York

Application January 24, 1952, Serial No. 18,204

Term of patent 14 years

(Cl. D44—9)

To all whom it may concern:

Be it known that I, Donald E. Folley, a citizen of the United States, residing at Fayetteville, State of New York, have invented a new, original, and ornamental Design for Cup, of which the following is a specification, reference being had to the accompanying drawing, forming a part hereof.

Figure 1 is a top plan view of a cup embodying my new design.

Figure 2 is a side elevational view;

Figure 3 is a bottom plan view; and

Figure 4 is a vertical sectional view thereof taken on line 4—4 of Figure 1.

I claim:

The ornamental design for cup, as shown.

DONALD E. FOLLEY.
